US0D1008187S

(12) **United States Design Patent** (10) Patent No.: **US D1,008,187 S**
(45) Date of Patent: ** Dec. 19, 2023

(54) **VEHICLE DIAGNOSTIC CONNECTOR**

(71) Applicant: **Liang Hou**, Guangdong (CN)

(72) Inventor: **Liang Hou**, Guangdong (CN)

(**) Term: **15 Years**

(21) Appl. No.: **29/820,024**

(22) Filed: **Dec. 20, 2021**

(51) LOC (14) Cl. **13-03**

(52) U.S. Cl.

USPC **D13/133**; D14/357

CLAIM

The ornamental design for a vehicle diagnostic connector, as shown and described.

DESCRIPTION

FIG. 1 is a perspective view of a vehicle diagnostic connector showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings depict portions of the vehicle diagnostic connector that form no part of the claimed design.

1 Claim, 7 Drawing Sheets
